UNITED STATES PATENT OFFICE.

ALEXANDER J. LOGUIN, OF NORWOOD, OHIO, ASSIGNOR, BY MESNE ASSIGNMENTS, TO
ALLIS-CHALMERS MANUFACTURING COMPANY, A CORPORATION OF DELAWARE.

ELECTRICAL PROTECTIVE DEVICE.

1,161,320.

Specification of Letters Patent.

Patented Nov. 23, 1915.

Application filed March 23, 1912. Serial No. 685,684.

To all whom it may concern:

Be it known that I, ALEXANDER J. LOGUIN, a subject of the Czar of Russia, residing at Norwood, in the county of Hamilton and State of Ohio, have invented certain new and useful Improvements in Electrical Protective Devices, of which the following is a full, clear, and exact specification.

My present invention relates to time element devices for use in electric circuits.

For the protection of electrical apparatus included in electric circuits, it is necessary to provide means for opening circuits upon the occurrence of abnormal conditions. At the same time it is desirable that the circuit should not be broken upon the occurrence of abnormal conditions which exist only for a brief time. Relays which are used for opening electric circuits upon the occurrence of abnormal conditions are usually provided with retarding means of some nature to prevent opening of electric circuits except when the abnormal conditions continue for a predetermined time.

It is the object of my invention to provide a simple, compact, and inexpensive circuit protecting device having time element means adapted to meet all of the requirements of successful commercial operation.

The various novel features of my invention will be apparent from the specification and drawing and will be particularly set forth in the appended claims.

The invention is illustrated in the figure of the accompanying drawing which is a side elevation, parts being in section, and showing the preferred form of my invention.

Mounted upon a suitable insulating support 10 is a horizontally projecting core 11 of a magnet having a winding 12 mounted on said core 11. Secured to the outer end of the core 11 and insulated therefrom are stationary contacts 13 and 14, pivotally secured to the latter of which is a movable contact member 15 adapted to engage the stationary contact 13 to complete a circuit. Electrically connected to the stationary contacts 13 and 14 are circuit terminals 16 and 17. Loosely mounted in one end of the horizontal core 11 is a rod 18, which is adapted to be moved in a vertical direction to disengage the stationary and movable contacts 13 and 15 to break the circuit when abnormal conditions occur and continue for a certain predetermined time. This rod 18 lies in the

path of and is adapted to be actuated by the magnet armature member 19 which is pivotally secured, at 20, to the core 11 of the magnet. This armature member is provided with a weight 21 which is adjustable lengthwise of the armature to render said armature responsive to overloads of different degrees. This armature member is also provided with a downwardly projecting portion 22 which is adapted to engage, at different times, two projections 23 and 24 of a lever 25 having a third projection 26. The projection 26 of the pivotally mounted lever 25 is provided at its end with a forked portion 27 which engages a piston rod 28 to transmit motion to and from a piston 29 forming the movable member of a dash-pot 30 which also is suitably mounted on the insulating support 10. Secured to one end of the piston rod 28 is a spring 31 which normally biases the piston 29 in an upward direction. The spring 31 is provided with adjustable means including a rod 32 secured to one end of the spring 31 and which is engaged by a thumb nut 33 which bears upon the cap 34 of the dash-pot 30.

The dash-pot is provided with a liquid 35, preferably oil, in which the piston is movable, for retarding purposes. The dash-pot is also provided with a guide member 36 for the piston rod 28, the guide member having openings 37 through which the liquid may pass when the piston 29 is moved in an upwardly direction.

Under normal operating conditions the armature member will be in the position shown in the figure with the projection 22 engaging projection 24 of the lever 25 to force and to hold down the piston 29 against the action of the stretched spring 31. This device remains in this position until an overload or an abnormal circuit condition arises, whereupon the armature member 19 will be attracted toward its core. But in attempting to move toward the core the projection 22 of the armature member 19 engages the latch portion 38 of the lever projection 23, preventing further movement of the armature member 19 for the time being. When the armature projection 22 is in engagement with the latch 38, said projection 22 is out of engagement with the lever projection 24, which relieves said lever and piston 29 of the weight of the armature 19, and the spring 31 gradually draws the piston 29 into

upward through the retarding liquid 35. As the piston 29 is moved upward, motion is transmitted through lever projection 26, swinging the lever 25 about its pivotal point 39 until the latch 38 has moved out of engagement with the armature projection 22, whereupon, providing the abnormal circuit condition still exists, the armature member 19 is rapidly drawn into engagement with its core 11, driving the rod 18 into engagement with the movable contact member 15 and separating contacts 13 and 15 to break the circuit. When abnormal circuit conditions have ceased to exist the armature member 19 drops away from its core and the armature projection 22 falls into engagement with and presses against lever projection 24, forcing the piston, due to the weight of the armature, downwardly against the action of the spring 31 to its normal position. The armature member 19 may be made responsive to abnormal circuit conditions of different degree by moving the weight 21 along said armature member 19. The time element may be varied by adjusting the tension of the spring 31 through the coöperating threaded members 32 and 33. With this arrangement a circuit-protecting device is capable of responding to abnormal circuit conditions of different degree to make the time of effective retardation any desirable value.

There may be various modifications and arrangements other than that here shown and described, and it is my intention to cover all such modifications and arrangements which do not depart from the spirit and scope of the invention as set forth in the appended claims.

40. What I claim as new is:

1. In a protective device for electric circuits, a member having a projection and being responsive to abnormal circuit conditions, a pivotally mounted member having a portion thereof engageable by said projection to hold said pivotally mounted member in one position, said projection being adapted to engage another portion of said pivotally mounted member upon the occurrence of abnormal conditions, and means for moving said pivotally mounted member out of engagement with said projection after a predetermined time to permit said first mentioned member to completely respond to the abnormal condition.

2. In a protective device for electric circuits, the combination of a member responsive to abnormal circuit conditions, a retarding device therefor including a dash-pot the movable member of which is normally biased in one direction, and intermediate means coöperating with said first mentioned member and the movable member of said dash-pot and effective to transmit energy to force said movable member in an oppo-

site direction and for preventing movement of said first mentioned member during the continuance of an overload until said movable dash-pot member has moved a predetermined distance in the direction in which it is biased.

3. In a protective device for electric circuits, the combination of a member responsive to abnormal circuit conditions, means for delaying the movement of said member upon the occurrence of abnormal circuit conditions, said means including a dash-pot the movable member of which is biased in one direction and a pivotally mounted member normally engaging said first-mentioned member and the movable member of said dash-pot to overcome said bias, said pivotally mounted member being responsive to the movement of the movable member of the dash-pot to release said first-mentioned member only after a predetermined time.

4. In a protective device for electric circuits, means responsive to abnormal circuit conditions for breaking a circuit, and means for delaying the movement of said responsive means and including a dash-pot the movable member of which is biased in one direction and a pivotally mounted member responsive to the movement of both the responsive means and the movable member of said dash-pot, said pivotally mounted member being adapted to prevent complete responsive movement of said responsive means until a certain time interval has elapsed.

5. In a protective device for electric circuits, the combination of an overload responsive device including a movable member having a projection, means for delaying action of said movable member including a dash-pot the movable member of which is biased in one direction, and a pivotally mounted member having a plurality of projections one of which is normally engaged by said first-mentioned movable member and another of which engages the movable member of said dash-pot, and still another one of which is adapted to prevent movement of said first-mentioned movable member in response to an overload until said pivotally mounted member is rotated a predetermined amount by the movable member of said dash-pot.

6. In a protective device for electric circuits, the combination of an overload responsive device including a movable member adapted to break the circuit, and means for preventing said movable member from breaking said circuit upon the occurrence of an overload until a certain predetermined time has elapsed, said means including a dash-pot the movable member of which is biased in one direction and a lever provided with three projections two of which are adapted to be engaged by said first-mentioned movable member and the third of

which is responsive to the movements of the movable member of said dash-pot, one of said projections preventing the movement of said first-mentioned movable member in response to an overload until the movable member of said dash-pot has rotated said lever a predetermined amount.

7. In a protective device for electric circuits, the combination of means responsive to abnormal circuit conditions, said means including a movable member having a projection, and means for retarding the movement of said movable member in response to abnormal circuit conditions, said retarding means including a dash-pot, a spring for biasing the movable member of said dash-pot in one direction, means for varying the effectiveness of said spring, and a lever having a projection normally engaged by the projection on said first-mentioned movable member to transmit energy to hold said movable dash-pot member against the action of said spring, said lever having a second projection with a latch portion adapted to be engaged by the projection of said first-mentioned movable member upon the occurrence of an abnormal circuit condition, whereupon said movable dash-pot member is actuated by the spring to gradually draw the latch portion of said lever out of engagement with the projection of said first-mentioned movable member to permit said first-mentioned movable member to break the circuit.

8. In a protective device for electric circuits, a member movable in response to abnormal circuit conditions, a member biased to one position and having a retarded movement toward such position, connecting means between said movable member and said

biased member, said movable member during its movement in one direction actuating said connecting means to move said biased member against its normal bias, and said connecting means being effective by reason of its connection with said biased member to hold said movable member against complete movement in response to abnormal circuit conditions until said abnormal conditions have existed for a predetermined time.

9. In a protective device for electric circuits, a member movable in response to abnormal circuit conditions, means for normally holding said member against such movement, retarding means normally biased to one position, said holding means being operated by said member to actuate said retarding means against its normal bias, and said holding means being effective on the occurrence of abnormal circuit conditions until said retarding means has moved a predetermined distance toward biased position.

10. In a protective device for electric circuits, a member movable in response to abnormal circuit conditions, and means normally biased to one position and having a retarded movement to such position, said means being actuatable to another position by said member and being effective to hold said member against effective movement on the occurrence of abnormal circuit conditions until said conditions have existed for a predetermined time.

Milwaukee, Wis., Feb. 24, 1912.

In testimony whereof I affix my signature, in the presence of two witnesses.

ALEXANDER J. LOGUIN.
